US0D1113141S

(12) United States Design Patent (10) Patent No.: US D1,113,141 S
(45) Date of Patent: * Feb. 17, 2026

(54) TOTE BAG

(71) Applicant: Qiuyan Chen, Guangzhou (CN)

(72) Inventor: Qiuyan Chen, Guangzhou (CN)

() Term: 15 Years

(21) Appl. No.: 35/522,165

(22) Filed: Aug. 5, 2024

(80) Hague Agreement Data

Int. Filing Date: Aug. 5, 2024

Int. Reg. No.: DM/239427

Int. Reg. Date: Aug. 5, 2024

Int. Reg. Pub. Date: Aug. 30, 2024

(51) LOC (15) Cl. 03-01

(52) U.S. Cl.

USPC D3/217; D3/246
